DESCRIPTION

U.S. PATENT DOCUMENTS

FIG. 1 is a front, top, left isometric view of a portable radio
housing in accordance with my new design;

- D. 280,507 9/1985 Claxton et al. D14/137
D. 282,620 2/1986 Toth et al. D14/137
D. 288,683 3/1987 Bostler et al. .... D14/138 X
D. 291,804 9/1987 George D14/138
D. 292,211 10/1987 Imazeki D14/137
D. 339,128 9/1993 Claxton et al. D14/138
D. 346,602 5/1994 Robertson .... D14/299 X
D. 348,878 7/1994 Lindeman et al. D14/137
D. 354,056 1/1995 Claxton et al. D14/138

FIG. 2 is a front elevational view thereof;
FIG. 3 is a left side elevational view thereof;

FIG. 4 is a right side elevational view thereof;

FIG. 5 is a top plan view thereof; and,

FIG. 6 is a bottom plan view thereof.

The rear surface is not considered to be a part of my claimed
design. The broken line showings of FIGS. 1-6 are for
illustrative purposes only and form no part of the claimed
design.
